UNITED STATES PATENT OFFICE.

SAMUEL J. HARRIS, OF RANDOLPH, MASSACHUSETTS, ASSIGNOR OF ONE-HALF TO
C. LE ROY SEAVER, JR., OF STOUGHTON, MASSACHUSETTS.

WATERPROOF SHOE.

1,136,799.

Specification of Letters Patent.

Patented Apr. 20, 1915.

Application filed January 22, 1914, Serial No. 813,744. Renewed March 5, 1915. Serial No. 12,417.

To all whom it may concern:

Be it known that I, SAMUEL J. HARRIS, a citizen of the United States, resident of Randolph, in the county of Norfolk and State of Massachusetts, have made a certain new and useful Invention in Waterproof Shoes; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 Figure 1 is a central longitudinal section of my shoe. Fig. 2 is a section of the line 2—2, Fig. 1. Fig. 3 is a similar view on a larger scale, partly broken away. Fig. 4 is a view similar to Fig. 3 showing a modification. Fig. 5 is a detail perspective view of the insole and its waterproof covering. Fig. 6 is a detail sectional view, partly broken away of the upper leather and its lining. Fig. 7 is a similar view showing an intermediate waterproof layer. Fig. 8 is a similar view showing the upper leather provided with a layer of water proof material.

20 The invention has relation to boots and shoes, whereof the outer covering is usually 30 of leather, and it consists in the novel construction and combinations of parts whereby such boots or shoes are designed to be made impermeable to water, as hereinafter set forth.

35 In the accompanying drawings illustrating the invention, applied to a shoe, the numeral 2, indicates the sole; 3, the insole, 4, the upper leather, the numeral applying to both vamp, and quarters, and 5, the lining.

40 The lining is first coated or sized on the outside with friction compound, which is calendered thereto, after which it is covered with a sheet of rubber or waterproof material. The vamp and quarters or parts 45 constituting the upper leather of the shoe are united to the lining in the usual manner, the waterproof layer of the lining being next to the leather. The toe-box and counter may be attached in the usual manner between the lining and the upper leather, to 50 complete the upper after it is ready to be lasted to the insole 3. This insole is channeled around the toe and along each side to the heel to provide a downward extending rib 6, adjacent to a marginal portion 7.

The underside of the insole is cemented and covered with a layer 8, of rubber or waterproof material, this layer covering the inside of the angular channel as well as the rest of the insole on its lower surface. The 60 lower edges of the lining and of the upper leather are cemented and having been placed on the last, the edges of the lining and upper are drawn over the edge of the insole and lapped upon and pressed against 65 the marginal portion 7 of the channel, to unite the same thereto in such wise as to protect the bottom of the shoe against leakage. The waterproof layer of the upper and the waterproof layer of the insole being 70 joined together by their lapped marginal portions, a protecting wall is formed around the shoe which is designed to be impervious to water. The welt 9, is attached in the channel of the insole against the inward 75 bent margin of the upper, in such wise as to press the same against the rib 6, and the marginal portion 7, of the insole. The welt is then secured to the insole by stitching it to the rib wall of the channel, after which 80 the ragged edge is trimmed. The inseam is thus formed. The bottom of the welt is now covered with cement, and a strip 10, of rubber or waterproof material cemented on one side is pressed against the rubber or 85 waterproof covering of the insole in such a manner as not only to cover the inseam, but also the whole bottom of the welt and heel seat. The hollow or vacant interval surrounded by this strip is to be filled with 90 scrap or material suitable for this purpose, and the shank piece 12, being attached, the outer or wearing soles are secured, and the shoe is finished up in the usual manner. 95 When tacks or similar devices are used in the lasting, a strip of rubber or waterproof material 12¹ is designed to be cemented to the lower edge of the upper, covering the heel seat and lying over the edge of the inseam, and also cemented to the upper side 100 of the welt, this being designed to form a watertight union and protection. (See Fig. 4.)

When the lining is not coated, an intermediate layer of rubber or waterproof material 4¹ is employed (see Fig. 7) and in some cases, when a lining is not used, the inside surface of the upper leather is provided with a layer of rubber or waterproof material, 5¹. (See Fig. 8.) 110

The tongue 15, which is designed to be used in a shoe of this character, is backed with a layer of rubber or waterproof material, and is plaited or folded. The side edges of the tongue are attached to the fly of the upper on each side and its lower edge to the upper end of the vamp between the flies. In this way it is designed to close the instep opening in such a manner as to prevent water reaching the foot, unless by entry over the top of the shoe.

What I claim and desire to secure by Letters Patent is:

1. In a shoe, upper leathers, a sole, an insole, a welt, a bottom waterproof layer covering the underside of the insole, an upper waterproof layer covering the inside surface of the upper leathers and lapping the marginal portion of said bottom waterproof layer, a waterproof joint connecting the lapped marginal portions of the bottom waterproof layer and the upper waterproof layer, and a waterproof strip connected to the bottom of the upper and connecting it to the welt.

2. In a shoe, upper leathers, a sole, an insole, a lining, a welt, a bottom waterproof layer covering the underside of the insole, an upper waterproof layer covering the outside surface of the lining and lapping said bottom waterproof layer, and a waterproof joint connecting the lapped marginal portions of the bottom waterproof layer and the upper waterproof layer.

3. In a shoe, upper leathers, a sole, an insole, a bottom waterproof layer covering the underside of the insole, an upper waterproof layer covering the inside surface of the upper leathers and lapping said bottom waterproof layer, a welt, a waterproof joint connecting the lapped marginal portions of the bottom waterproof layer and

the upper waterproof layer and a waterproof strip between and connecting the bottom waterproof layer and the welt.

4. In a shoe, upper leathers, a sole, a marginally channeled insole, a bottom waterproof layer covering the underside of the insole and the inside of the channel, an upper waterproof layer covering the inside surface of the upper leathers, a waterproof joint in the channel of the insole connecting the marginal portions of the bottom waterproof layer and the upper waterproof layer, and a welt in the channel between the joint and the margin of the sole.

5. In a shoe, upper leathers, a sole, a marginally channeled insole, a bottom waterproof layer covering the underside of the insole, an upper waterproof layer covering the inside surface of the upper leathers, a waterproof joint in the channel of the insole connecting the marginal portions of the bottom waterproof layer and the upper waterproof layer, a welt covering said joint in the channel, and a waterproof layer between the welt and sole.

6. In a shoe, an insole provided with a marginal channel having its inner wall projecting downward, a bottom waterproof layer covering the underside of the insole and the channeled portion, an upper waterproof layer, a waterproof joint in the channeled portion connecting the bottom layer and the upper layer, a welt covering said joint, and means for connecting the welt to the downward wall of the channel.

In testimony whereof I affix my signature, in presence of two witnesses.

SAMUEL J. HARRIS.
